UNITED STATES PATENT OFFICE.

JOHN H. OVERTON, OF TRENTON, NEW JERSEY.

RUBBER HEEL-LIFT.

1,315,682.

Specification of Letters Patent. Patented Sept. 9, 1919.

Application filed March 1, 1919. Serial No. 280,026.

To all whom it may concern:

Be it known that I, JOHN H. OVERTON, a citizen of the United States, residing at Trenton, in the county of Mercer and State of New Jersey, have invented certain new and useful Improvements in Rubber Heel Lifts, of which the following is a specification, reference being had to the accompanying drawings.

10 This invention relates to the art of shoes and the like, and particularly to an improved rubber heel or lift, and an object of the invention is to provide an improved heel lift of this kind, which is simple, efficient 15 and practical in construction, the same being so constructed as to fit tighter and closer to the heel than has been accomplished by heel lifters heretofore used.

A further object of the invention is to 20 provide an improved resilient web-like insert member embedded in the rubber heel or lift, to insure a springing or yieldable effect, and at the same time to insure rigidity for the rubber body of the heel lift. In 25 other words, to provide an insert, which will not only allow the rubber body of the heel lift to yield or cushion, but will act to restore or cause the body to resume its normal shape and condition. For instance, the 30 lift may be pressed or crushed incident to the weight, and just so soon as the weight or pressure is relieved, the lift will resume its normal shape.

The invention further aims to provide a 35 rubber heel lift, so constructed and provided with what may be called a double cupping, acting to distribute the tension, whereby a practically and absolutely tight fitting heel lift may be produced. This 40 tight fitting effect is especially emphasized at the corners of the heel, particularly owing to the construction of a metal insert and the provision of the lateral lugs carried by the insert and extending in a direction 45 toward the corners of the heel. This provision in the present case has been designed, especially in view of the fact that rubber heel lifts heretofore used begin to detach from the leather heel at the corners thereof.

50 The invention further aims to provide a rubber heel lift of this kind, which will eliminate the very expensive operation of

utilizing individual washers upon the washer pins which has heretofore been employed. Furthermore, the metallic spring or yieldable insert can be embedded in the heel lift in one operation, whereas the utilizing of individual washers requires an operation for each washer.

In the construction of this rubber heel lift, it is the aim to construct the metallic yieldable insert in order to exactly conform with the face of the heel. However, it is the object to position or embed the resilient metallic insert in the body of the heel, so that its face will be substantially equally spaced from one of the faces of the body of the heel, with the exception of where the lateral lugs extend from the insert. In other words, the spacing of the insert throughout 70 its entire area is uniform relative to one face of the body of the lift, but the extension lugs are designed to slope toward the bottom of the heel to within a short distance from the corners of the heel.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features 85 and combination of parts as will be herein-after set forth, shown in the drawings and claimed.

In the drawings:

Figure 1 is a perspective view of the heel portion of a shoe showing applied to the leather heel thereof the improved rubber heel lift, but illustrating the fact that the lift is only partially secured.

Fig. 2 is a similar view, showing the rubber heel lift firmly and completely secured.

Fig. 3 is a perspective view of the rubber heel lift showing the upper face thereof.

Fig. 4 is a longitudinal sectional view on line 4—4 of Fig. 1.

Fig. 5 is a transverse sectional view on line 5—5 of Fig. 1.

Fig. 6 is a detail view of the insert plate.

Referring to the drawings 1 designates the body of the heel lift, which may be constructed of any suitable material preferably rubber or the like, or a composition thereof, said body in the present instance is constructed to conform to the shape of the heel of a shoe. It is to be noted that the face 2 of the body is cupped out or concaved upon opposite sides of the center of the lift. 10 These cups or concaves are designated by the numerals 3, and 4 denotes a longitudinally extending rib intermediate the concaves. By the provision of such a construction and since the edge of the rib is curved, 15 the marginal edges of the heel lift will closely and tightly fit the underface of the usual leather heel of a shoe.

The underface 5 of the heel is provided with a plurality of bulges or protuberances 20 6. The lift is provided with a plurality of openings 7, which receive suitable fastening means to secure the lift to the heel of the shoe.

Certain of the openings are formed 25 through the bulges or protuberances, so that when the fastening means are extended through the openings, the bulges or protuberances will substantially flatten out, and cause the lift to tightly bind to the leather 30 heel. By the provision of these bulges or protuberances, the heel lift does not become countersunk to any material extent, when driving the fastening means in place.

Embedded in the body of the heel lift 35 is a metallic yieldable insert 8, which, in cross-section, is of a shape to conform to the cross-sectional shape of the body of the heel lift. In other words, the body of the heel lift in cross-section is double-arched, 40 and the insert correspondingly conforms to such shape. For instance, the insert has a centrally located V-shaped portion, which conforms to the ridge of one face of the body of the lift. This insert is in the form 45 of a web-like plate, which conforms to the contour of the edge of the body of the lift. This plate is provided with a plurality of circular openings 9, 10, and 11, which are located near the marginal portion of the 50 plate, three at the forward portion of the plate, one at the rear and one upon each side. The plate is also provided with a central portion 12, having a central aperture or opening 13. This central portion 12 is connected to the outer portion of the plate by the radial arms 14. Adjacent the openings 9 and the opening 11 are lugs 15, 16 and 17. The lugs 15 are shaped to conform and be directed toward the corners of the body of 60 the heel, while the lug 16 extends forwardly, and centrally of the body of the heel, whereas the lug 17 extends directly rearwardly. By the provision of these lugs pressure is urged upon the adjacent portions

of the body of the heel so as to cause the 65 body of the heel lift to closely and tightly fit the leather heel of the shoe.

The openings or apertures 9, 10 and 11 and 13 are designed for the reception of fastening means, whereby the heel lift may 70 be secured to the leather heel of the shoe. Where the openings or apertures are formed, the insert is provided with enlargements, so as to strengthen and reinforce that portion of the insert through which the fastening means extend, and also to reinforce the 75 body of the heel lift.

The invention having been set forth, what is claimed as new and useful is:

1. As a new article of manufacture, a heel 80 lift comprising a cushion body having substantially concavo-convex portions with the concave portions in the attaching face of the body, a part of the attaching face being raised to separate the concavities in said 85 face and said concavities terminating at such part.

2. The combination with a cushion heel body, of a metallic web-like insert having means extending in various directions to 90 urge pressure on the body near the marginal edge thereof, whereby the body may fit closely and tightly against the underface of the leather heel of the shoe, said insert plate having a plurality of openings, the body of the heel lift having openings adjoining the openings of the insert plate and through which openings fastening means may be driven, one face of the body of the lift having concaves on opposite sides of the 100 center of the body, the center of the body having a rib, said rib being positioned to divide the concaves, the outer face of the body being provided with a plurality of protuberances through which certain of 105 the openings of the body are formed.

3. As a new article of manufacture, a heel lift comprising a cushion body having its attaching face provided with a plurality of concavities, the central portion of said 110 face being raised to separate the concavities, said concavities terminating at said raised portion, the opposite face of the lift being provided with a plurality of protuberances underlying the concave portions of the 115 attaching face of the body.

4. As a new article of manufacture, a heel lift comprising a cushion body having its attaching face provided with a plurality of concavities, a portion of said face being 120 raised to separate the concavities, said concavities terminating at said raised portion, the opposite face of the lift being provided with a plurality of protuberances underlying the concave portions of the attaching face of the body, and a resilient insert within the body, said body and insert having a plurality of openings for the reception of 125

fastening means, certain of said openings being disposed through the lower parts of the protuberances.

5. As a new article of manufacture, a cushion heel body having substantially concavo-convex portions in its attaching face, a part of the attaching face being raised to separate the concavities in said face and said concavities terminating at such portion, the

summit of the raised portion lying in a 10 plane with the outer edges of the attaching face.

In testimony whereof I hereunto affix my signature in the presence of two witnesses.

JOHN H. OVERTON.
